CYLINDER LINER

Kenneth Cutler Alward, Moweaqua, Ill.

Application July 3, 1941, Serial No. 401,037

6 Claims. (Cl. 309—3)

1

This invention relates to cylinder sleeves and as a principal object aims to provide an improved form of replaceable cylinder, which is more durable and is more easily removed and replaced in renewing same.

It contemplates more especially the provision of a cylinder liner contractible radially and retractile longitudinally and which contacts the cylinder bore cohesively.

In the practice of prior and present art relative to cylinders in internal-combustion and steam engines, air compressors, pumps, pneumatic and hydraulic devices and/or the like, a cylinder surrounded by a cooling construction was machine finished from a molded casting.

One object of the present invention is to provide a novel type of cylinder liner comprising a longitudinal transversal at a bias angle with respect to the axis of the cylinder contributing to its contractility and contorted retractility.

Another object is to devise a series of interrupted and alternating slots along a cylinder sleeve in a longitudinal direction, the characteristic resilient compressibility of which said alternating slots provides a liner sleeve less critical in minute circumferential accuracy and thus assuring a tight sleeve being closely pressed in the receiving cylinder.

A still further object is to provide a contractile and/or retractile cylinder liner for the rifle barrels of guns with retaining means therefor, and devices for facilitating replacement.

Still a further object is to simplify the process of manufacturing cylinder sleeves by circular bending same deviationally from flat sheets of metal and/or by slanted incision of a cylinder.

Other objects and advantages will be evident in the following description of the illustrated embodiment of the present invention.

Identification of the drawings:

Fig. 1 is a perspective view of a bias cleaved cylinder sleeve in a diminishingly distorted shape for facilitating insertion into a bore.

Fig. 2 is a perspective view of a casting bore recipient to a cylinder sleeve as comprising a bias longitudinal transversal and alternating offset slots.

Fig. 3 is an elevational view of a cylinder sleeve incorporating staggered slots distributed in a longitudinal direction.

Fig. 4 is a magnified perspective view of a slot of Figs. 2 and 3 in a fragmented segment of a cylinder.

Fig. 5 is a side elevational view of a rifled firearm barrel with the breech end shown in bisection, showing the cleaved rifle liner and the retaining collar in assembly.

2

Fig. 6 is a side view of the replaceable liner for a rifled gun barrel, showing the spiral parting cleft.

Fig. 7 is an elevational view of the rifle liner shown in Fig. 6.

Fig. 8 is a transverse view of a rib and groove forming die for processing the blank of Fig. 9.

Fig. 9 is an elevational view of a flat liner plate before being circumflex formed as in Figs. 6 and 7.

Fig. 10 is a plan view in aerial perspective, showing a deflectional method of inserting a blank in a roller forming device.

Fig. 11 is a transverse view of the rollers of the mandrel roller circumforming device.

Fig. 12 is a bisectinal view of the liner retaining collar.

The structure selected for illustration includes a cylinder sleeve 10 of Fig. 1 or 9 of Fig. 2 which fits into a cylinder body 11 and its flange recesses into annular groove 17.

The longitudinal transversal 12 projected at a bias angle on sleeve 10 makes possible the especial ease in removing the worn sleeve and replacing it with a new one, rather than employing special tools as screw presses to remove conventional sleeves, which will "freeze" as mechanics skilled in the art call it, thru incrustations or natural adhesions after same is pressed in tightly.

The bias transversal of my invention permits a screwdriver to be placed in groove 17 against flange 14 at the juncture of transversal 12 and the sleeve sprung inwardly toward the axis to free and loosen same. Here the marvel of the bias transversal proves itself. By prying under flange 14 near 12 at the acute angle side of transversal 12 all tightness in the sleeve is removed and same is free to be slightly compressed and easily removed from the cylinder block.

In replacing the new sleeve 10, as the same reposes with a lessened diameter or if made rectilinear as 9, said sleeve may be subjected to a twisting manipulation and started in the top of cylinder 11. The feature of the bias transversal 12 again demonstrates the advantage thereof; for by pressing downward on the obtuse angle side of flange 14, relief reduction in circumference will result allowing complete sleeve 10 to be easily pushed to the bottom of the cylinder. Upon approaching the last stage of insertion into the cylinder bore, the compressibility of the interrupted and alternate construction of 13 will allow the sleeve 9 to be adjusted to any discrepancies and to assume a tightly fitting joint 12 upon completing final insertion.

Fig. 3 illustrates clearly the situation created by the provision of slots as a type of alternating

voids 13 along the sleeve body. Such offset vacancies therein allow the circumference of the sleeve 8 to resiliently contract slightly upon insertion thereof as does 13 of Fig. 2. Said sleeve being in a compressed condition upon installation within a continuous bore will exert a constant circumferential stress to closely contact said cylinder bore.

The transversal 12 affords especial tightness and snugness of said sleeve relative to the bore 11 thereby enhancing the heat-transfer cooling qualities thereof, sealing the former gap, and perfecting regularity of the internal surface. Accumulatory advancement along adjacent edges of said 12, or as may be described as approachment of previously displaced angles opposite the transversal, brings into reality the powerful wedge action, most desirable in a thin liner to accomplish close union and security with a separate bore receivable of a wearing surface member, which may be a bushing or the like of some type.

In the manufacturing process the sleeve 10 is curved by a roller circumflex bending device from sheets of steel, brass or suitable material of chosen thickness, for example No. 16 gauge, after being first sheared into pieces shaped like a rhomboid. The sleeves may then be hardened or tempered and edges finished to final dimensional accuracy. If so desired, the sleeves 10 may be cast of iron, steel or bronze; and then be finished by the usual cutting and grinding process and the longitudinal transversal provided therein.

When a tube is used, the sleeve may be split with any proper machine or tool. It may then be twisted or sprung by a forced approachment of the respective opposite angles. The rolling process, Figs. 10, 11, characterizes forming over a core, the roller 37 thereof being enveloped by the blank whereas the work plate 22 for example is wound over the included roller. This method results in the production of a cylinder the surface of which is symmetrically true, as 37 constitutes a mold base mandrel and the rollers can squeeze a work piece, such as a sleeve, to precise curvature.

In the air corps, naval, military, and anti-aircraft services the fire power of the rifles has been enormously hampered by the wearing out of the spiral rifling of the gun barrel, which disposes the projectile to rotate in spiral convolutions throughout the path of its trajectory. The service of worn guns must be lost and a hazardous, time-consuming return to the arsenal is required. As a classical example during World War I the two "Big Berthas," shooting a distance of seventy miles (reportedly) were enabled to fire only eleven times total before their rifling was demolished.

This invention provides a rifle liner readily replaceable in positions near to its point of service.

Now referring specifically to Fig. 5, the outer barrel 27 comprises a straight bore 26 in which is installed a smooth bore sleeve 29 comprising an angular interrupting incision 12, whereas said sleeve 29 receives the shell casing, and the hinder portion of the projectile.

In abutment with the said sleeve 29 is inserted the rifled liner 25, which is best illustrated by Fig. 6. Said liner comprises a parting cleft 28, which is parallel with the spiral ridges and grooves of the rifling. Due to the statically distorted position of the liner 25 of Fig. 6, its external diameter is slightly reduced in comparison to its natural operating position as in Fig. 6. The angularity of the parting cleft 28 effectuates such aforesaid reduction in diameter, and this dia-

metrical reduction permits, without the process of heating the outer barrel as is the practice of the past, the readily achieved insertion of the liner 25 into the bore 26.

5 The threaded retaining collar 33, detailed in Fig. 12 is screwed tightly on the muzzle end of the outer barrel 27, and contacts the muzzle end of the liner 25 at the collar shoulder 34. The procession of the collar 33 springs the liner 25 to a 10 straight and normal position, as illustrated in Fig. 5.

The procession of the collar 33, just described, will cause the liner 25 to increase in diameter, also due to the angularity of the parting cleft 28; 15 and the long pitch angle of said 28 results in a powerful wedge to snugly tighten the liner 25 within the barrel 27.

A flange 23 on the muzzle extremity of liner 25 is in thrust contact with the shoulder 34 of 20 collar 33, allowing the use of a thinner liner than otherwise without said flange. It (said flange), being an integral enlargement of the liner (as in 14 of Fig. 1), and given an extra depth more than a normal turned flange, will absorb the end thrust 25 of the liner as well as the torque of the collar 33 during installation. It is the flange feature which especially crowns this rifle liner arrangement with success.

Upon the removal of the worn liner, when the 30 collar 33 is unscrewed, the liner 25 will spring back into its smaller distorted position of Fig. 6 sufficiently for removal, and a new liner may be inserted on battleship deck, or in rear land positions, thereby correcting a critical situation under 35 such conditions.

Of course, the smooth bore sleeve 29 could be made integral with the liner 25 and yet maintain consistency of invention.

The respective concave and convex edges of the 40 dividing cleft 28 are shown in Figs. 7 and 11. Thus is formed an interlocking joint, securing it against any movement due to the prying effect of the projectile driving band against the sloping edges of the rifling ridges. V-shaped edges would substitute therefor.

45 Various other types of edges have been used in interrupted annular devices heretofore, but none have been both easy to form and yet effective in providing a secure interlocking interstice as are these. Concave and convex edges are, therefore, in a class by themselves in regard to novelty and utility.

The replaceable liner 25 is manufactured from 55 rhomboidal sheets of selected steel. Into the form of Fig. 9 (22) it is ridged and grooved, while hot, by the roller die 36 of Fig. 8, which is mounted in a rolling machine. The die 36 comprises ribs and grooves which transversely conform to the rifling of 22. After being trimmed to dimensions, 60 22 is circumflex formed by a forming core three-roller circumflex machine as per Fig. 11 into liner 25, Fig. 6. Finish broaching of the rifling may then be done, if desired.

The distorted position of the liner 25 of Fig. 6 is 65 accomplished in the circumflex rolling process as illustrated in Fig. 10. For example, if the rhomboidal strip 22 is inserted in the machine with the nearer end edge perpendicular to the forming rollers, an undistorted liner will result, as in Fig. 6. Otherwise, if the line of the end edge of 70 22 is deflected from the rectilinear, the distorted shape of the cut cylinder rifle liner 25 of Fig. 6 will inure. The rhomboidal angle already being known (which controls the reduction in diameter per linear inch of distortion), the required 75

amount of distortion is readily determined when the desirable shrinkage is decided upon from the basis of standard tolerances for clearances.

The angle of deviation of the rhomboid from the rectangular is arrived at from the calculation of the helix angle of the rifling—the tangent of which angle is the circumference of the liner cylinder divided by the linear distance or "lead" of the rifling, in which length of barrel said rifling spirally convolutes one complete turn.

The result of this liner replacement will be to reestablish original space relationship between cooperating elements—the rifle bore and the projectile, which principle of maintenance is the consistent result of this invention.

It should be understood that the invention is not to be limited to the specific embodiments thereof herein described and illustrated, but may include various modifications and changes of structure coming within the spirit or scope thereof as defined by the appended claims.

I claim, therefore as my invention:

1. Incorporated in a cylinder sleeve arrangement a unitary closed stationary cylinder sleeve, disconformingly contractible radially and distortionally retractable longitudinally, reposing tightly in a circular bore with a stressed fit accruing from a self-constituted longitudinal wedging actuation and having a flange projecting from an extremity thereof.

2. Incorporated in a cylinder sleeve arrangement a tightly wedged cylinder sleeve liner distortionally contractible circumferentially and disconformingly elastically retractable longitudinally comprising a closed single longitudinal parting interrupting incision inclined at a bias angle in respect to the axis of the cylinder, thus facilitating replacement of said sleeve, the result of which is restorative of the original and correct space relationship between said sleeve and moving elements cooperating therewith.

3. Incorporated in a cylinder sleeve arrangement a cylinder sleeve, a bias angular longitudinal incision with respective concave and convex edges thereon, a series of interrupted slots, in a relative position along a plurality of lines approximately parallel to the longitudinal incision of the cylinder sleeve, with slots alternating in respect to slots inserted along adjacent lines, for the purpose of assuring contiguous contact of relative articular edges of the cylinder sleeve liner, by virtue of the inherent elastic compressibility of such construction.

4. Incorporated in a cylinder sleeve arrangement an uncleaved outer rifle barrel having in combination therewith a liner therefor which disposes the projectile cooperating therewith to progress and rotate in a clockwise direction and com-

prising an incision substantially parallel to the rifling therein and being distortable longitudinally thus slightly reducing its diameter for convenient insertion into aforesaid outer barrel without the necessity of heat-expanding same and without conventionally shrinking a rifled liner into an outer barrel, and comprising interlocking edge faces, and comprising a projecting flanged anchoring extremity, contributory to a rifle liner being especially thin and therefore more easily manufactured, conveniently transported, and more readily inserted into a rifle.

5. Incorporated in a cylinder sleeve arrangement a cylinder sleeve comprising a closed longitudinal incision in bias angular relativity to the axis of the cylinder thereof, which said cylinder sleeve is elastically distortable thus effecting a diminution of its perimeter as a consequence for the purpose of facilitating insertion into a cylinder bore, and said cylinder sleeve being contradistortable thus completely reclaiming the full circumference of the bore whence it is inserted and being provided with alternate interrupted slots and thus affording a resilient compressible construction, thereby accomplishing a tightly wedged interrupted cylinder liner for receiving a moving element in cooperation therewith.

6. Incorporated in a cylinder sleeve arrangement in an uninterrupted rifle cylinder barrel combination with a conveniently insertable and removable liner therefor which is capable of exerting a wedging action upon being thrust by the procession of a retaining member abutting the muzzle end of said liner and variably engaging the muzzle end of said rifle barrel thereby singularly retaining said liner rigidly within said barrel.

KENNETH CUTLER ALWARD.
